ELEVATOR DISPATCHING SYSTEM

Edgar M. Bouton, Chicago, Ill., and Frank E. Lewis, East Pittsburgh, Pa., assignors to Westinghouse Electric and Manufacturing Company, a corporation of Pennsylvania

Application May 3, 1928. Serial No. 274,702

3 Claims. (Cl. 177—336)

Our invention relates to dispatching systems for vehicles, and it has particular relation to systems for dispatching elevators, hoists and similar devices.

5 The object of our invention, generally stated, is the provision of a dispatching system that shall be simple and efficient in operation and adapted for ready and economical installation.

A more specific object of our invention is to 10 provide a dispatching system for a number of vehicles operable over parallel pathways between two fixed terminals whereby the vehicles will be started in predetermined succession from the terminals at regular intervals of time.

15 It is also an object of our invention to reduce the number of stops to be made by any one of a number of vehicles when that vehicle falls behind its schedule and thereby permit it to catch up with and resume its proper position in relation to the other vehicles in the system.

Other objects of the invention will, in part, be obvious, and will, in part, appear hereinafter.

20 For a fuller understanding of the invention, reference may be had to the following detailed description, taken in connection with the accompanying drawing, in which the single figure is a diagrammatic view of a control system and apparatus embodying our invention, as applied to a bank of elevators.

25 In dispatching systems of the type employed to schedule the operations of a bank of elevators, it is customary to provide a signal which shall indicate to the attendant on each of the cars the time at which his car is scheduled to 30 leave the terminal floor. These systems usually comprise a timing device which produces a signal on each of the several cars at successive equal intervals of time, to insure that a car will leave the terminal floor at such intervals, and 35 thus tend to keep the cars evenly spaced in the hatchway.

40 This type of dispatching system is not wholly satisfactory for the reason that it frequently happens that one car may be required to make a large number of stops in making a trip, while 45 the following car makes very few stops, whereby the leading car arrives at the terminal later than prescribed by the schedule, and must be immediately started on a new trip, without waiting 50 to take on passengers at the terminal or else the scheduling of cars is defeated.

55 Our invention overcomes this objectionable feature in that the dispatching system is connected to the signal system in such manner as to withhold certain stop signals from such cars as

fall behind their predetermined schedules, and thus permit them to recover their proper positions in relation to the other cars in the system. In this way, any car which, because of traffic conditions, is delayed in its movement toward 60 the terminal is allowed to run as an express car to the terminal floor, in order that it may arrive in time to depart more nearly on its regular schedule.

65 Referring to the drawing, our dispatcher system is illustrated as comprising a constant-speed motor M, preferably of the shunt-wound type, having a variable rheostat R in circuit with its shunt field winding MF and having its armature M' suitably coupled, through reduction gearing, 70 to a pair of contact discs 1 and 2. The contact disc 1, hereinafter referred to as the "up" disc, comprises a contact member 3 arranged on the periphery of the disc and suitably insulated from the driving shaft 4 that connects the disc to the 75 armature M'. The particular construction of this contact disc 1 is not material, since any form of contactor which will produce an impulse of electric current once in each revolution of the driving shaft 4 will be sufficient for the purpose 80 of our invention. The contact disc 2, hereinafter referred to as a "down" contact disc, comprises a suitable contact member 5 insulatingly supported by a sleeve 6 mounted upon the shaft 4 and fixed thereto by means of a suitable thumb screw 7, 85 thus providing for adjustment of the relative angular positions of the contact members 3 and 5. The purpose of this adjustment will be described hereinafter. The contact member 3 cooperates with a suitable stationary contact member 8 for 90 completing a circuit through the contact member and thereby producing an impulse of electric current by operation of the disc 2 each time the shaft 4 makes a complete revolution.

95 The impulses of electric current are utilized for operating dispatching signals to indicate the time schedule under which the cars should operate in a manner hereinafter described.

100 The three elevator cars illustrated in the drawing are designated by the characters A, B and C, respectively. The car A is provided with the usual controlling mechanism (not shown), for moving the car upwardly and downwardly in its shaft and is also provided with a contact device of the floor-selector type movable in correspondence to the movements of the car. This 105 contact device may be similar to that described in the patent to Smalley, et al, No. 634,220. The contact device illustrated comprises a continuous contact strip 10, the length of which is rep- 110

representative of the distance between the upper and the lower terminal floors. Adjacent to the lower end of the contact strip 10 is a short contact strip 11, and adjacent to the upper end is a short 5 contact strip 12. The relative positioning of the contact strips 11 and 12 with respect to the contact strip 10 is such that a movable contact bridge 13, operable over the contact strip 10 as the car moves between the lower terminal and the upper 10 terminal, will bridge the contact strips 10 and 11 when the car is at the first floor and the contact strips 10 and 12 when the car is at the top floor. The contact strip 11 is connected in circuit with a relay A—14, while the contact segment 12 is 15 connected in circuit with a relay A—15.

A suitable dispatching signal A—16 is mounted on the elevator car A, for operation by the impulses of electric current produced by the dispatching system to indicate the schedule on 20 which the car should operate. Suitable floor lanterns, such as are usually provided in elevator systems at the upper and lower terminal floors, are designated, respectively, as A—17 and A—18.

The elevators are also provided with a signal 25 system in which a flash signal lamp 19 is disposed on each of the cars for indicating to the operator when a stop is to be made for taking on or discharging passengers.

In order that the passengers, when waiting at 30 a floor landing, may operate the signal lamps 19 to give the attendants on the cars a stop signal, a pair of passenger-operated push buttons is mounted at each of the landings intermediate the terminal floors, one for up travel and one for 35 down travel. The "up" and the "down" buttons for the second floor are respectively designated as 2U and 2D, while those for the third floor are designated as 3U and 3D.

Associated with the push buttons are push-button relays 2UR, 2DR, 3UR and 3DR, respectively, for holding the push button signals until they are answered. The coils of the push-button relays are connected respectively to corresponding hatchway-door contact members 2HU and 40 2HD, 3HU and 3HD in such manner that the relays will be reset when the push-button calls are answered by the operators.

For the purpose of enabling the attendant in each car to set the signal-giving device 19 in his 50 car to indicate stops to let passengers get off, the car A is provided with car push buttons A2, A3 and A4, the car B with push buttons B2, B3 and B4, and the car C with push buttons C2, C3 and C4. Associated with the car push buttons are 55 push-button relays AR2, AR3, AR4, BR2, BR3, BR4, CR2, CR3 and CR4, respectively, for holding the car push-button signals until they are answered by the attendant.

In order that the various circuits for the passenger-operated push buttons, the car push buttons and the signal lamps in the cars may be connected in accordance with the positions of the cars, the cars A, B and C are provided, respectively, with floor selectors FSA, FSB and FSC. 60 The floor selectors are similar to those usually employed in the elevator art and may be located at any suitable point, for example, in the pent house or in the elevator shaft.

The floor selector FSA for car A is provided 70 with a set of "up" contact segments and a set of "down" contact segments. The "up" contact segments are arranged in a group under an "up" brush AU, and the "down" contact segments are arranged in a group under the "down" brush AD, 75 both brushes being mounted on a movable arm

MA which traverses the contact segments. The selector FSB for car B is provided with "up" contact segments which are arranged in a group under an "up" brush BU, and down contact segments which are arranged in a group under a "down" brush BD, both brushes being mounted on a movable arm MB. Similarly, the selector FSC for car C is provided with "up" contact segments which are mounted in a group under an "up" brush CU and down contact segments which are mounted in a group under a "down" brush CD, both brushes being mounted on a movable arm MC.

The movable arm of each selector is operated by a screw S which is driven by some part of the operating mechanism of the car which the selector serves.

The frictional engagement between the arms and their operating screws causes the arms to bear upon the "up" contact segments when the cars are travelling upward and upon the "down" contact segments when the cars are moving down.

Inasmuch as signalling systems and floor selectors therefor are old and well known in the art, we have, for the sake of simplicity, illustrated the 100 passenger-operated signals only in connection with the second and third floors and the car push buttons only in connection with second, third and fourth floors.

In accordance with our invention, the dispatching system and the signalling system are connected in order that the dispatching system may control the operation of the signal system in such manner that some or all of the passenger-operated stop signals will be withheld from any car that is 110 behind its schedule and no car is at the starting terminal at the time for the dispatching signal, thereby permitting the "behind schedule" car to run as an express car to its terminal floor. As 115 shown, this is accomplished in the present instance by placing a relay DS, which is controlled by the dispatching system, in position to temporarily prevent the completion of the circuit between the signal lamps 19 in the cars and the passenger-operated push buttons 3D and 2D for "down" stops at the third and second floors when 120 one of the cars gets behind its schedule and no car is at the starting terminal at the time for the dispatching signal.

While we have, for convenience, illustrated the 125 relay as controlling only the second and third floor down signal lamps, it will readily be understood that such signals for additional floors may be placed under the control of the relay as may be desired.

Our system is best described with reference to an assumed operation. Assuming that the elevator car A is starting down from the top of the shaft, and that a waiting passenger at the second floor presses push button 2D to register a stop signal for that floor, then a circuit will be partially completed for the signal lamps A—19, B—19 and C—19 in the cars A, B, and C. The pressing of the push button 2D completes a circuit for the push-button relay 2DR from supply conductor 135 L2 through conductors 20 and 21, the contact members of push button 2D, conductor 22, the coil of relay 2DR, conductor 23, hatchway-door contact members 2HD, and conductor 24 to supply conductor L1. A self-holding circuit for the 140 push-button relay 2DR is established from supply conductor L2 through conductors 20 and 25, the contact members a of push-button relay 2DR, conductor 26, the coil of push-button relay 2DR, conductor 23, hatchway-door contact members 145

2HD, and conductor 24 to supply conductor L1.

As the car A descends and approaches the second floor landing, the brush AD bridges the contact segment 27 and the contact strip 28, thereby lighting the signal lamp A-19 in the car A to indicate that the car switch A-59 should be centered for stopping the car. The completed circuit for the signal lamp A-19 extends from supply conductor L2 through conductors 20, 25 and 29, the contact members b of push-button relay 2DR, conductor 30, the normally closed contact member b of relay DS, conductors 31 and 32, contact segment 27, the brush AD, contact strip 28, conductor 33, signal lamp A-19, conductors 34, 35 and 36 to supply conductor L1. When the car A answers the second floor call, the opening of the hatchway door at the second floor associated with car A causes its contact members 2HD to open the holding circuit for relay 2DR.

As the car A completes the stop for the second floor and approaches the terminal floor, it will cause the brush A-13 to bridge the contact strips A-10 and A-11 to complete a circuit for energizing the relay A-14, which circuit extends from line conductor L1 through conductors 40 and 41, a single-pole switch 42, conductor 43, contact strip A-10, contact brush A-13, contact strip A-11, conductor 44, the coil of relay A-14, conductor 45, the normally closed contact members a of relay A-46, conductor 47, the normally closed contact members b of relay C-46 (corresponding to the relay A-46), conductor 48, the normally closed contact members b of relay B-46, conductor 49, the normally closed contact members b of relay A-46 and conductors 50 and 20 to supply conductor L2. The relay A-14 then closes its contact members b, completing a circuit for energizing the relay A-46 which circuit extends from supply conductor L1 through conductors 51 and 52, the coil of relay A-46, conductor 53, the contact members b of relay A-14, conductors 54 and 20 to supply conductor L1. The actuation of the relay A-46 opens its contact members a and b, thereby breaking the normal circuit for the relay A-14. However, relay A-14 closes its contact members a to complete a shunt around the contact members of the relay A-46, B-46 and C-46 by way of conductor 45, contact members a of relay A-14 and conductors 55 and 20. Thus, as long as the car remains at the lower terminal floor, the relays A-14 and A-46 will remain energized.

Assuming also that the car C left the lower terminal when the car A left the upper terminal and that the car B leaves the lower terminal just as car A arrives, then the relay A-14 will complete a circuit for the floor lamp A-18 for the first floor to indicate that car A is the first car to start an up trip. This circuit extends from supply conductor L2, through conductors 20 and 56, the contact members c of the relay A-14, conductor 57, floor lamp A-18, and conductors 58 and 36 to supply conductor L1.

Assume that, after the arrival of the car A at the first floor, the dispatching contact member 3 has been moved by the motor M through engagement with the contact member 8, completing a circuit for the dispatching signal A-16 in the elevator car A. This circuit extends from supply conductor L2 through conductors 61 and 62 to the motor shaft 4, contact members 3 and 8, conductors 63, 64 and 65, contact members d of relay A-14, conductor 66, dispatching signal lamp A-16 and conductors 35 and 36 to supply

conductor L1. The attendant on the car will now move the car switch A-59 to start the elevator car A on its up trip.

Assuming that car A has taken on a number of passengers at the lower terminal floor who desire to get off at the third floor, as the passengers call their stop, the attendant presses the car push button A-3 to so set the signalling system that it will indicate, as the car nears the third floor, that a stop should be made at that floor.

The pressing of the car push button A-3 completes a circuit for the car-push-button relay AR-3 from supply conductor L2, through conductors 20, 70 and 71, the contact members of push button A-3, conductor 72, the coil of the relay AR-3, the normally closed hatchway-door contact members 73, and conductors 74, 75 and 36 to supply conductor L1. A self-holding circuit for the relay AR-3 is established from supply conductor L2, through conductors 20, 76 and 77, contact members a of relay AR-3, hatchway door contact members 73 and conductors 74, 75 and 36 to supply conductor L1.

The pressing of the car push button A-3 also partially completes a circuit for the signal lamp A-19 in the car A. As the car A ascends and approaches the third floor landing, the brush AU bridges the contact segment 80 and the contact strip 81, thereby lighting the signal lamp A-19 in the car to indicate that the car switch A-59 should be centered for stopping the car. The completed circuit for the signal lamp A-19 extends from supply conductor L2 through conductors 20, 76 and 82, contact members b of relay AR-3, conductor 83, contact segment 80, brush AU, contact strip 81, conductor 33, signal lamp A-19 and conductors 34, 35 and 36 to supply conductor L1.

When the car A makes the stop at the third floor, the opening of the hatchway-door contact members 73 opens the holding circuit for the car-push-button relay AR-3.

Assuming that the elevator car B arrives at the lower terminal immediately after car A leaves, an operation similar to that described with reference to the elevator car A will be effected for operating the floor lamp B-18, and the dispatching signal B-16 will be lighted upon the next engagement of the contact members 3 and 8 as the motor shaft 4 makes its next complete revolution. Similarly, the elevator car C will be dispatched from the lower terminal upon the third revolution of the motor shaft 4.

The time between the successive operation of the dispatching signals for the cars may be varied by movement of the rheostat R, thereby increasing or decreasing the resistance in circuit with the motor field winding MF, thus permitting the time of departure to be varied at will.

As the elevator car A approaches the upper terminal, the contact strips A-10 and A-12 will be bridged by the movable contact member A-13, energizing relays A-15 and A-85 to cause the operation of the upper terminal floor lamp A-17 and the actuation of the dispatching signal lamp A-16 when the contact members 5 and 9 are engaged as the contact disc 2 is rotated by the shaft 4. The operation of these relays and of the contact disc 2 is similar in all respects to the operation of the similar signals at the lower terminal floor and will not be described in detail.

It will be noted that the dispatching signal A-16 cannot be energized unless either relay A-14 or relay A-15 is in circuit-closing position.

In this manner, only the dispatching system for that car which is at the terminal may be operated.

Assume that, prior to the departure of elevator car A from the first floor, the elevator car 5 B arrives at that floor, then the movable contact member B-13 associated with the car B will bridge the contact strips B-10 and B-11 to complete a circuit for the relay B-14. However, the circuit for the relay B-14 extends through the 10 normally closed contact members b of relay A-46 by way of a circuit which extends from supply conductor L1 through conductors 40 and 86, switch 87, conductor 88, contact strip B-10, contact member B-13, contact strip B-11, conductor 89, the coil of relay B-14, conductor 90, the normally closed contact member a of relay B-46, conductors 91 and 47, the normally closed contact members b of relay C-46, conductor 48, normally closed contact members b of relay B-46, 15 conductor 49, contact members b of relay A-46 and conductors 50 and 20 to supply conductor L2. However, it is apparent that, so long as car A remains at the first floor and has its relay A-46 energized, the relays B-14 and B-46 will be in- 20 effective and, therefore, that the floor lamp B-18 will not be illuminated until the car A leaves.

As the car A leaves the first floor and places car B in condition to be the next car to leave the floor, the deenergization of relay A-46 permits 25 the contact members B-10 and B-11 to complete a circuit for the relay B-14 and relay B-46. The relay B-14 closes its contact members c, energizing the floor lamp B-18. The dispatching signal is transmitted thereafter to the car B, as 30 previously described.

When no car is standing at the lower terminal to receive the dispatching signal at the time the contact member 3 moves into engagement with the contact member 8, the signal will be registered 35 or stored up by a relay 100 and maintained until such time as a car arrives at the floor. The registering relay 100 is provided at the dispatching station or in any other suitable location and has its coil connected in circuit with the contact 40 members 3 and 8 and with the contact members of a second relay 101. The relay 101 is energized at all times when no cars are at the lower terminal floor by way of a circuit which extends from supply conductor L1 through conductors 102 and 103 the coil of relay 101, the conductors 104 and 47 and thence, in series, through the normally closed contact members b of relays A-46, B-46 and C-46 to supply conductor L2, as previously traced for these contact members.

The relay 101 prepares a circuit for the coil of the registering relay 100, which circuit is completed by the engagement of the contact members 8 and 3. This circuit extends from supply conductor L1 through conductors 102 and 105, the contact members of coil 101, conductor 106, the coil of relay 100, conductors 107 and 63, contact members 8 and 3, and conductors 62 and 61 to supply conductor L2. The relay 100, when energized, completes a self-holding circuit which extends from supply conductor L1 through conductors 102 and 105, the contact members of relay 101, conductor 106, the coil of relay 100, conductor 108 and contact members a of relay 100, and conductors 109 and 20 to supply conductor L2. Thus, 55 a circuit is maintained between supply conductor L1 and the contact members of each of the up dispatching relays A-14 and B-14 and C-14 so that the first car of the bank to arrive at the lower floor will operate its associated relay and 60 75 will receive instantly the dispatching signal indi-

cating that it is to depart immediately on its next upward trip.

The relays 110 and 111 operate in a similar manner to perform the same function for the down dispatching system when there are no cars at the 80 upper terminal floor.

Any one of the cars A, B and C may be removed from the automatic dispatching system by opening the switch associated with that car, these 85 switches being designated as 42, 87 and 112.

While the dispatching system is illustrated as being automatic, it is obvious that a manual production of the starting or dispatching impulses might be achieved by providing dispatching buttons for the elevator captain or starter to be 90 operated at will. Such buttons are shown and designated as 113 and 114 for the up and down directions, respectively.

The interval of time elapsing between the giving of the dispatching signal for any car to start 95 its up trip and to start its down trip may be varied within desired periods by a suitable adjustment of the contact disc 2 with reference to the contact disc 1.

The series of push buttons 115, 116 and 117 100 are associated with the elevator cars A, B and C, respectively, for the purpose of permitting the captain or starter to flash the dispatching signal on the associated elevator car when he desires to call that car to one of the terminal floors for 105 some special service.

Assume again, for example, that the dispatching contact member 3 is moved through engagement with the contact member 8 at a time when there is no car standing at the lower terminal floor 110 to receive the dispatching signal, (which condition only occurs when one of the cars is delayed in its passage between terminals) and that the car which, if on time, would be scheduled to leave next is behind its schedule and is still a 115 considerable number of floors above the first floor. Under these conditions, the relay 100 closes to register and maintain the dispatching signal. The closing of the relay 100 also completes a circuit for energizing the relay DS to withhold 120 "down" stop calls for the second and third floors from the next car to approach the terminal floor, and thereby permit that car to run as an express car to the lower floor and restore the system to its schedule. The completed circuit for the relay 125 DS extends from supply conductor L1 through conductors 24 and 120, the coil of relay DS, conductor 121, contact members b of relay 100, conductors 122, 109 and 20, to supply conductor L2. When the relay DS is energized, it opens its contact members a and b in the circuits between the "down" call buttons 3D and 2D and the signal lights A-19, B-19 and C-19 in the cars A, B and C and thereby prevents the completion of the circuits for the down signals until the relay 130 100 is deenergized by the arrival of a car at the terminal.

Assuming that car A is run as an express car to the lower terminal under these conditions, its arrival causes the brush A-13 to bridge the contact strips A-10 and A-11, thereby lighting the signal lamp A-16 and resetting the registering relay 100 as hereinbefore described. The resetting of the relay 100 opens its contact members b and deenergizes the relay DS which then closes 145 its contact members a and b and restores the circuits for the passenger-operated push buttons 2D and 3D and the stop signal lamps A19, B19 and C19 in the cars.

It will, therefore, be seen that we have pro- 150

vided a dispatching system in which at any time a car falls behind its proper running position with reference to the other cars in the system the first car to approach the terminal thereafter 5 is enabled to run as an express car to the terminal, thus assuring that a car will leave the terminal more nearly on time than if all cars were permitted to continue to make stops prior to reaching the terminal floor.

10 It will be observed, however, that the dispatching system is permitted to cut off only those signals operated by passengers waiting at a floor, since it is not desirable to cut off signals indicating that passengers in the car desire to leave 15 at the corresponding floors. For this reason, the car signal buttons A2 and A3, when operated, remain effective regardless of whether the car is on time or behind its schedule.

While we have illustrated our invention as applied to a dispatching system similar to that set forth in application Serial No. 215,392, filed August 25, 1927, and assigned to the Westinghouse Electric & Manufacturing Company, it will be understood that the invention may be readily 25 adapted for use with any other form of dispatching system.

The embodiment of our invention described is merely illustrative and is susceptible of many changes and substitutions in the arrangement of 30 the apparatus described. Therefore, we do not desire to be limited to the details shown except as defined in the appended claims.

We claim as our invention:

1. In a dispatching system for a bank of elevator cars, means for registering a dispatching signal indicating that a car should be prepared

to start a trip from a dispatching floor, means for each of said cars for receiving said signal, means disposed outside of said cars for registering a stop signal for said cars, and means operable by failure of a car to be in position to start such a trip for preventing the reception of said stop signal by the cars closely approaching the dispatching floor until one of said cars is placed in starting position.

2. In a dispatching system for a bank of elevator cars operating from a dispatching terminal, means for registering a dispatching signal for said cars indicating that a car should be prepared to start a trip, means for each of said cars for receiving said dispatching signal, means disposed outside of said cars for registering a stop signal for said cars, and means operable by failure of a car to be in position to start such a trip for preventing the reception of said stop signal by such of said cars as are approaching the terminal until the arrival of one of said cars at said terminal.

3. In a dispatching system for a bank of elevator cars operating from a dispatching floor, means for giving a dispatching signal to indicate when a car should leave on a trip from the dispatching floor, means disposed outside of said cars for registering a stop signal for said cars, and means operable by failure of a car to be in position to start such a trip for preventing the reception of said stop signal by such of said cars as are approaching the dispatching floor until the arrival of one of said cars at said dispatching floor.
